UNITED STATES PATENT OFFICE

CHARLES M. BANKS, OF PHILADELPHIA, PENNSYLVANIA

HYDRAULIC JACK

Application filed November 3, 1928. Serial No. 317,050.

This invention relates to hydraulic jacks and the main object of the invention is to provide a jack which is simple and durable in construction and efficient in operation.

5 Another object is to provide a jack which may be rapidly operated and which has an efficient release valve positive and convenient in operation.

The foregoing and other objects together with means whereby the same may be carried into effect will best be understood from the following description of a preferred embodiment of the invention taken in connection with the accompanying drawing in which—

15 Figure 1 is a vertical, central section through the jack, certain of the elements being shown in elevation.

Figure 2 is a plan view thereof.

20 Figure 3 is a detail of the release valve 24 moved from its seat.

Figure 4 is a detail view of a modification of the upper end of the plunger or ram showing an auxiliary extensible and retractile work engaging member.

25 Figure 5 is a detail of a handle for use in operating the jack.

In carrying out the invention I provide a relatively elongated base 1 having the upwardly directed jack cylinder 2 at one end 30 and the recess 3 at its opposite end spaced from the cylinder 2 and connected therewith by an angularly disposed port or passage 4.

35 A threaded filler plug 5 seated in an upwardly countersunk portion 6 of the base serves as a means for filling the device with oil as well as draining the oil from the same when necessary.

A cylindrical ram or plunger 7 is slidably mounted in the jack cylinder 2, the same having the piston rings 8 at its lower end and

40 the circular, relatively enlarged work engaging head 9 at its upper end. A collar 10 threadedly engages the upper end of the jack cylinder 2 and has the inwardly directed annular lip 11 adapted to overlie and retain

45 in place the wipe washer 12 which excludes dust and other foreign matter from the cylinder. A guide and stop rod 13 threadedly engages the head 9 and 14 and depends along the side of the jack cylinder 2 in parallelism

50 therewith, the said rod being slidably passed

through a bracket 15 secured to the cylinder and provided at its end with a stop 16 in such manner that it will limit the upward movement (to be described) of the plunger and prevent the same from rotating in the said jack cylinder.

The recess 3 is provided with an upstanding, exteriorly threaded annulus 17 upon which is threadedly mounted the pump cylinder 18 of relatively smaller diameter and length than the jack cylinder 2 as shown. An inlet valve denoted generally at 19 is positioned in the lower end of the pump cylinder 18 abutting against the upper edge of the annulus 17.

The said inlet valve 19 comprises an outer body portion 20 having a central seat 21 the upper portion 22 of which is flared upwardly and the lower portion 23 flared downwardly as shown in Figure 1. A valve

24 having a complementary tapered face is 65 adapted to seat upwardly in this lower portion 23 and the same has a flange 25 adapted to engage the body portion 20 to limit the seating action of the valve as will be understood.

The valve 24 is normally held seated by means of an expansion coil spring 26 mounted upon a pin 27 directed upwardly from a semi-circular bracket 28 affixed at its ends to the lower surface of the body 20 and extended downwardly therefrom, the upper end of the said spring 26 entering into a recess 29 in the lower surface of the valve.

A piston 30 is mounted in the pump cylinder 18 and the same is provided with a piston rod 31 extending upwardly through a conventional gland 32 seated in the cap 33 which is threadedly mounted over the upper end of the said cylinder 18. A pivot lug 34 is secured to the wall of the jack cylinder 2

70 above the level of the pump cylinder 18 and an operating lever 35 having the bifurcated end 36 is pivotally attached by a pin 37 to the lug, the said operating lever 35 being angularly bent in the form of a V as shown. A

75 link 38 is pivotally connected at its ends by pins 39 to the upper end of the piston rod 31 and the lower point of the operating lever 35. The outer end of the said operating lever 35

80 is squared as at 40 to receive the socket end 41 of an operating handle 42 by means of

which the piston 30 may be reciprocated within the cylinder for a purpose to be described.

A release valve casing 43 is extended angularly from the base 1 beneath the annulus 17, the axis of this casing being parallel with the extended axis of the port or passage 4. The cylindrical casing 43 is provided with a threaded mouth 44 and terminates at its inner end in a tapered valve seat 45, a small port or passage 46 communicating thru this seat with the recess 3 in the base 1. An elongated cylindrical valve 47 is inserted in the casing 43 the expanded outer end having threads at 48 to engage the threaded mouth 49 of the casing and a tapered inner end 49 to engage the seat 45. The said valve 47 also has a longitudinal groove 50 beginning at the tapered end 49 and passing along the valve a substantial distance then turning circumferentially and passing partially around the valve as shown at 51. A small port or escape aperture 52 is provided in the casing 43 in such manner that by properly positioning the valve in the casing the groove 50 will register with this aperture for a purpose to be described. The outwardly disposed end of the valve 47 is reduced and squared as at 53 so that it will fit the socket end 41 of the said operating handle 42, which handle is provided with an arcuate hook 54 by means of which the jack may be withdrawn from under any object.

In the use and operation of the device the jack is inverted and an operating fluid such as oil is poured into the jack through the filler plug 5 until it reaches approximately the end of the ram or plunger 7, as the same stands telescoped within the cylinder 2. Then by reciprocating the piston 30 in the pump cylinder 18 in the manner set forth, air will be forced through the valve 19, recess 3 and passage 4 forcing the ram or plunger upward as will be understood. The air cannot escape through the valve 19 since its pressure only serves to more firmly close this valve. The air must be compressed in the pump cylinder until its pressure is sufficient to overcome the tension of the spring 26 and the pressure of the air in the base 1 and cylinder 2, so that the rise of the ram or plunger will be steady and even as will be understood. When it is desired to release the pressure in the jack and lower the plunger the release valve 47 is turned until the groove 50 therein is brought into registry with the escape aperture 52 whereby the air may escape. It will be noted that since the groove in this valve 47 is not only turned out of registry with the aperture 52 but the tapered end 49 of the valve seats in the seat 45 when the jack is being raised the valve is tightly closed so that air cannot possibly escape, yet by turning the valve a part of a revolution the air may freely escape. It will also be noted that the jack may be placed in position, the plunger

caused to rise, the pressure released and the jack then withdrawn by means of the single, simple handle 42. From the foregoing the efficiency, simplicity and ease of operation of the jack will be apparent.

In Figure 4 is illustrated a modification of the construction of the work engaging head 9 upon the ram or plunger 7. In this case an extensible and retractile auxiliary member or head 55 with a threaded shank 56 is threadedly mounted in the end of the said ram 7, the regular head 9 thereof being provided with a recess 57 to receive this said head 55. By unscrewing this auxiliary head 55 the jack may be closely adjusted to the work so that the work may be raised to the full capacity of the jack. By screwing the head 55 downward the work may rest upon the regular large head 9.

While I have herein set forth certain preferred embodiments of my invention it is understood that I may vary from the same in minor details so as best to construct a practical device for the purposes intended, not departing from the spirit of the invention and within the scope of the appended claim.

I claim:

In a hydraulic jack embodying a jack cylinder and plunger and an operatively connected pump cylinder and compression piston, the assembly being vertically arranged and having a relief valve for the escape of air, a compression valve in the pump cylinder below the compression piston, the same comprising an outer body portion having a central aperture and seat, the upper portion of the seat being flared upwardly and the lower portion being flared downwardly, a frusto-conical valve for complementarily seating upwardly in the lower flared portion of the valve seat, the same being centrally recessed in its lower face, and having a flange for engaging the under side of the body portion to limit the seating action of the valve, a semi-circular bracket secured by its ends to the lower surface of the body portion at diametrically opposite points, a pin extended from the bracket up into the said recess of the valve, and a coil spring seated over the said pin and extended under compression up into the said recess of the valve and having a bearing against the valve for holding it to its seat.

In testimony whereof I affix my signature.
CHARLES M. BANKS.
